UNITED STATES PATENT OFFICE.

HERBERT S. PULLMAN, OF MERIDEN, CONNECTICUT.

BELL.

SPECIFICATION forming part of Letters Patent No. 654,324, dated July 24, 1900.

Application filed February 26, 1900. Serial No. 6,488. (No model.)

To all whom it may concern:

Be it known that I, HERBERT S. PULLMAN, a citizen of the United States, and a resident of Meriden, in the county of New Haven and 5 State of Connecticut, have invented certain new and useful Improvements in Bells; of which the following is a specification.

My invention relates to the general class of alarm or call bells; and my object is to 10 provide a striking mechanism for such bells that will produce the effect of an electric bell in the rapidly-repeated strokes of the hammer when the bell is operated.

Referring to the drawings, where one form 15 of embodying the invention in a bell is shown, forming part hereof, Figure 1 is a top or plan view of the base of the bell and the operating mechanism, the gong being removed. Fig. 2 is a view in side elevation of the bell, 20 the gong being cut in central section. Fig. 3 is a detail view, on enlarged scale, showing the ratchet-drive in central section.

In the accompanying drawings the letter 25 *a* denotes the base of the bell, which may be of any convenient form with ordinary means to support the structure in proper position for use.

On the base *a* is secured a post *b*, the outer end of which bears a gong *c*, secured in any 30 convenient manner, the post being hollow or tubular to receive the plunger *d*, which has a sliding movement therein, the arm *d'* on the plunger projecting through a slot in the side wall of the post *b*.

To a fixed part of the frame of the structure and preferably on the side of the post *b* a bell-crank lever *e* is pivoted, with its outer end *e'* underlying the arm *d'* on the plunger and its opposite end connected by a link *f* with 40 one end of the striker-lever *g*. This striker-lever *g* is pivoted to the base of the bell, as at *h*, and has on its outer end a segmental gear *g'*, which is in mesh with a pinion *i*. This pinion is secured to the hub *k'* of the ratchet-wheel *k*, which is pivotally supported on the post *l* on the base *a*. On the same hub *k'* an escapement-wheel *m* is loosely mounted, so as to turn freely in one direction while held from any sliding movement along the hub, 45 and by means of the spring-pawl *n* pivoted to the side of this escapement-wheel *m* the ratchet-wheel *k* is connected to the wheel *m*,

so as to turn with it in the reverse direction. A verge *o*, with pallet-teeth in suitable engagement with the escapement-wheel, is 55 mounted on a rock-shaft to which the arm *p'* of the bell striker or hammer *p* is secured. When the escapement-wheel is forcibly rotated in one direction, the verge will be caused to vibrate rapidly and the gong to sound. 60 The striker-lever is held in the proper position of rest by means of a spring *r*, one end of which is anchored to the base and the other attached to the lower end of the bell-crank lever, as shown in Fig. 1 of the drawings. 65

To operate the bell, pressure is applied to the cap of the plunger *d*, so that the arm *d'* thrusts against the end *e'* of the bell-crank lever, tilts the latter, and through the link *f* 70 swings the striker-lever *g*, so that the rack on its outer end drives the pinion *i* and the escapement-wheel *m* in such a manner as to vibrate the hammer and sound the gong. As soon as the pressure on the plunger is relieved 75 the recoil of the spring *r* returns the several levers and parts to the original position, except that the escapement-wheel makes no reverse movement, the ratchet-wheel turning freely under the pawl in this resetting of the mechanism.

What I claim as my invention, and desire to secure by Letters Patent, is—

1. A bell-base, bell-striking mechanism supported by the base and including a pinion, 85 a hollow post supported on the base, a striker-lever pivoted to the base with one end having a segmental gear meshing with said pinion, a bell-crank lever pivoted on the post, a link connecting the bell-crank lever with the 90 striker-lever, a plunger supported by the post and having an arm overlying an arm on the bell-crank lever and a gong secured to the post.

2. A bell-base, bell-striking mechanism 95 supported by the base and including a single pinion, a hollow post supported on the base, a U-shaped lever with its branches lying on opposite sides of said post, one branch bearing a segmental gear meshing with said pinion, and the other branch forming a connection for a link, a bell-crank lever pivoted on the post, a link connecting the bell-crank lever with the U-shaped lever, a plunger sup-

ported by the post and having an arm overlying an arm on the bell-crank lever, and a gong secured to the post.

3. In combination with a base and a gong mounted thereon, a pivoted hammer, hammer-operating mechanism including a verge and an escapement-wheel, a fixed stud, a ratchet-wheel mounted to turn on the stud and having an elongated hub, the escapement-
10 wheel mounted to turn on the hub, a pawl

connecting the ratchet-wheel and the escapement-wheel, a pinion secured to the hub of the ratchet-wheel, a striker-lever in engagement with said pinion, and means for operating the striker-lever.

HERBERT S. PULLMAN.
